INSTRUMENT ILLUMINATION

Charles I. MacNeil, Glen Ridge, N. J., assignor to
 Bendix Aviation Corporation, South Bend, Ind.,
 a corporation of Delaware

Application November 14, 1940, Serial No. 365,704

2 Claims. (Cl. 240—2.1)

This invention relates to indicating instruments, and particularly to the illumination of the index elements of such an instrument.

Although, in the accompanying drawing, the invention is illustrated in its application to an instrument of the pointer and dial type, it is not limited to such an application, nor are there any limitations other than those which appear uniformly in each of the appended claims.

In certain installations of instruments, it is 10 present day practice to employ electric lights or lamps having bases which attach to a supporting surface in such manner as to cause the light emitting part of the device to be disposed wholly, or partly beneath, or within, the outer wall or surface of the supporting member or members, and throw a beam of light along a channel or channels parallel to the panel, said channel or channels being adjacent the index characters of the instrument. The present invention readily lends itself to a comparable arrangement of parts (although not limited thereto) and in fact such an arrangement is shown in the accompanying drawing. However, in lieu of the light directing channels of such prior art devices, I propose to 20 employ the principles of polarization of light rays, as developed and expressed at length in the patents issued to Edwin H. Land and others, among which may be mentioned Patent No. 2,122,178, granted June 28, 1938.

The invention, therefore, has for an object the utilization of polarized light as a means for rendering an indicating instrument more readily readable, under all conditions.

Figure 1 is a side view partially in section taken on line 1—1 of Fig. 2.

Fig. 2 is a front view of the instrument showing the dial and pointer.

In the drawing reference character 1 designates the frame or body of an indicating instrument; 2, the disk or dial on which the index characters 4 appear; 3, the pointer, or "needle," as it is sometimes called; 6 and 7, the electric lamps (of which there may be more) spaced at even intervals about the body 1; 8 and 9, reflecting surfaces of suitable material and finish; 10 and 10', light polarizing windows adapted to polarize, in a single common plane, the light rays falling thereon from light sources 6 and 7; and reference numeral 11 designates the instrument cover glass, which is also of a light polarizing construction (e. g. "Polaroid"). Pointer 3 and dial char-

acters 4 are coated with a mechanical mixture of very small particles of multi-edged material (e. g. crushed silvered glass) adapted to present practically an infinite number of angles, so that the 5 polarized light rays passing through windows 10, 10', and falling upon these tiny "facets," will be diffused in all directions, thereby destroying their polarizations, and making it possible for the light to pass, without glare, through the cover glass 11 (assuming the glass 11 to be so arranged that minimum light emerges therefrom), and render the instrument characters, and pointer, readily discernible, against a "blacked out" background.

As an aid to the "blacking out" of the background, the surface of the dial 2 and the entire interior walls of the instrument are finished in such manner that the polarized light rays impinging thereupon will be reflected away, and will, when reflected, have a minimum of diffusion. 15 Thus the only light emerging from the instrument will be that which illuminates the index element 3 and reference characters 4.

What I claim is:

1. In an indicating instrument, the combination of a light polarizing cover glass, an illuminated chamber beneath said cover glass, means for illuminating said chamber, said illuminating means including a source of light built into the instrument and located beneath the plane of said 25 cover glass, means for polarizing the light from said source, indicia means in said chamber, and means for depolarizing that portion of the light from said source which strikes said indicia means, said de-polarizing means including multi-edged light diffusing particles applied to said indicia means and serving to depolarize said light.

2. In an indicating instrument, the combination of a light polarizing cover glass, an illuminated chamber beneath said cover glass, means 30 for illuminating said chamber, said illuminating means including a source of light built into the instrument and located beneath the plane of said cover glass, means for polarizing the light from said source, indicia means in said chamber, and means for de-polarizing that portion of the light from said source which strikes said indicia means, said de-polarizing means including multi-edged light diffusing particles coated on said indicia means and serving to de-polarize the light that 35 emerges from said chamber by way of said cover glass.

CHARLES I. MACNEIL.
